ELEVATOR

George Krell, Sapulpa, Okla.

Application September 14, 1938, Serial No. 229,906

24 Claims. (Cl. 294—90)

This invention relates to elevators for handling strings of pipe and particularly those employed in rotary drilling operations to rotatably connect a drill bit with a turntable and through which a drilling fluid is circulated in washing the cuttings made by the bit to the top of the well, the present invention being a continuation in part of application Serial No. 91,078, filed July 17, 1936.

As is well known, a string of drill pipe includes a plurality of pipe sections connected by couplings which offer supporting engagement by an elevator when the drill pipe is run into and pulled from the well in order to change the bit or perform other operations necessitating withdrawal of the drilling string. The ordinary elevator includes hinged sections latched together and forming a collar that loosely encircles the pipe and engages under the lower ends of the couplings. Since the inner diameter of the elevator is necessarily of larger diameter than the outer diameter of the drill pipe to facilitate its application and removal in accordance with the speed with which the string of pipe is handled, it is obvious that the elevator does not engage the entire area at the end of a coupling but only a limited extent on the outer peripheral edge thereof. Even on new couplings the actual contact area of the elevator is a minimum for safe operation but when the peripheral edges of the couplings have become worn by the abrading action of the cuttings contained in the drilling fluid, this supporting surface is reduced to such an extent that the worn coupling slips down into the elevator, and wedges or exerts radial thrusts which result in elevator failures.

Therefore the principal object of the present invention is to provide an elevator which has the necessary clearance relatively to a drill pipe for facilitating its application and removal but which automatically adjusts itself to engage the entire supporting surface at the end of a coupling and particularly the unworn portion immediately surrounding the pipe.

Other objects of the invention are to provide an elevator of this character with a universal hinge joint between the sections thereof; to provide an improved latch for the elevator capable of compensating for movements in the universal joint connection; to provide the elevator with a compensating latch having safety locking features; to provide a latch that is quickly and easily operated in accordance with the speed at which a string of pipe is handled; and to provide an operating means whereby the operator may use

either the right or left hand to unlock and unlatch the latch mechanism in opening and breaking down the elevator for encircling a pipe.

In accomplishing these and other objects as hereinafter pointed out, I have provided improved details of structure, the preferred forms of which are illustrated in the accompanying drawings, wherein:

Fig. 1 is a perspective view of an elevator constructed in accordance with the present invention and which is shown in operative engagement with the collar of a drill pipe section. 10

Fig. 2 is a plan view of the elevator with the bails removed and showing the operating levers in part section. 15

Fig. 3 is a plan view of the elevator in open position to engage a drill pipe.

Fig. 4 is a section through the elevator on the line 4—4 of Fig. 2, showing the sections closed.

Fig. 5 is a detail sectional view taken through 20 the hinge connection.

Fig. 6 is a detail perspective view of the parts composing the hinge connection and shown in disassembled spaced relation to better illustrate their construction. 25

Fig. 7 is an elevational view of the elevator from the latch side.

Fig. 8 is a vertical section through the elevator illustrating its engagement with the collar of a drill pipe section. 30

Fig. 9 is a detail section through the latch and taken at a point just above the upper latch releasing arm.

Fig. 10 is a similar section but taken at a point above the lower latch releasing arm. 35

Fig. 11 is a detail horizontal section through the hinge connection showing the elevator section in open position.

Fig. 12 is an elevational view of the latch side of a modified form of elevator which embodies 40 the features of the present invention, the bails being shown in section.

Fig. 17 is a cross-section through the modified form of elevator. 55

Referring more in detail to the drawings:

1 designates an elevator constructed in accordance with the present invention and which includes a collar or ring-like body 2 consisting of a pair of sections 3 and 4. The sections 3 and 4 are substantially semicylindrical in shape and of sufficient body thickness to provide the required strength in supporting the load of a string of drill pipe. The sections 3 and 4 have registering side faces 5-6 and 7-8 respectively, and intermediate arcuate faces 9 and 10 which, when the sections are placed in juxtaposition with the faces 5-6 and 7-8 slightly spaced apart as indicated at 11, form a substantially cylindrical bore 15 of somewhat larger diameter than the outer diameter of the drill pipe 12 encircled thereby.

The arcuate faces 9 and 10 are recessed intermediate the ends thereof as at 13 and 14 so that it is not necessary to machine the entire surface but only the ends thereof to the desired diameter. The upper ends of the respective sections are provided with arcuate ribs 15 and 16 having flat upper faces 17 and 18 to seatingly engage the lower end 19 of the drill pipe coupling 20. Extending radially from the outer side of each section, intermediate the side faces 5-6 and 7-8, are bail arms 21 and 22 having curved bail engaging notches 23 and 24 on the under sides thereof at a point substantially midway of the sections as clearly illustrated in Figs. 1 and 7. The upper sides of the arms are offset downwardly and outwardly to terminate in lugs 27 and 28 to cooperate with a similar lugs 29 and 30 at the lower sides of the notches to carry bail retaining pins 31 and 32, the pins having their ends mounted in aligning openings 33 in the respective lugs and retained by cotter pins 34. When the pins are in place they bridge the space between the lugs to retain the connecting bars 35 and 36 of supporting members or bails 37 and 38 wherewith the elevator is suspended from a conventional hook and tackle mechanism (not shown); to raise and lower the elevator in withdrawing or running in the drill pipe as in conventional drilling operations.

45 By reason of the normal spacing between the faces 5-6 and 7-8 of the respective sections, the sections are free to rock on the cross bars 35 and 36 of the bails until the upper ends of the sections engage each other which in effect reduces the diametrical spacing of the arcuate faces 9 and 10 at the upper ends of the sections so that the seats formed by the flat faces 16 and 17 engage the end of the collar in close proximity to the periphery of the drill pipe. To permit 50 this rocking or pivotal movement and to secure the sections together, I provide a universal hinge connection 39 on one side of the elevator and a compensating latch mechanism 40 at the opposite side. The hinge connection comprises substantially cylindrical ears 41 and 42 projecting from the respective sections in overlying relation and which have substantially flat end faces 43 and 44 spaced apart as indicated at 45 in Fig. 4 to accommodate the rocking movement of the sections. The opposite faces 45 and 46 of the 55 sections. The opposite faces 45 and 46 of the respective ears are also flat and the peripheries thereof are provided with stiffening ribs 47 and 48 terminating in stop lugs 49 and 50 respectively adapted to engage the body of the other section when the sections are open to their maximum extent. The ear 42 has a bore 51 extending completely therethrough in registry with a cylindrical bore 52 in the other ear. The bore 52, however, terminates short of the upper face of

the ear to form a stop 53 circumferentially of a smaller bore 54 that continues through the ear. The bores 51 and 52 cooperate in housing pivot members 55 and 56. The members 55 and 56 are of cylindrical form and of a size to be snugly received in the respective bores. The outer ends of the members engage against the stop 53 and against the face 57 of a bushing 58 that closes the lower end of the bore 51 and retains the pivot members 55 and 56.

10 The bushing 58 has an annular flange 59 that engages the bottom face 46 of the ear 42 to limit movement thereof into the bore. The adjacent ends 60 and 61 of the pivot members are spaced apart according to the spacing of the ears and 15 have transverse semicylindrical recesses 62 and 63 which cooperate to mount a transverse pivot member. The pin 64 is of a diameter to be oscillatable in the recesses and of a length to be retained in the confines of the pivot members, 20 the ends preferably being arcuate as indicated at 65 to conform to the cylindrical surfaces of the pivot members. The pivot members 55, 56 and 64 have registering openings 66, 67 and 68 corresponding to the opening 54 of the upper 25 ear 41 and with a similar opening 69 in the bushing 58. Extending through the respective openings is a pin 70 of smaller diameter than the openings to allow freedom of movement of the hinge parts relative thereto in rocking movement of the sections on their respective bails. The pin 70 has a hollow head 71 to accommodate a pressure lubricant fitting 72 through which lubricant is supplied to an axial channel 73 connecting spaced branch channels 74 and 35 75 extending through to the space surrounding the pin. The head of the pin also has a collar 76 to engage the upper face 45 of the ear 41. The opposite end of the pin is threaded as at 77 to mount a nut 78, cooperating with the collar to retain the sections in assembly.

In order to retain the axis of the pivot member 64 in plane with the vertical axis of the elevator, the pivot member 55 is keyed within the bore 51 by a pin 79 driven into an opening 45 formed partly in the ear 42 as clearly shown in Fig. 6. The pin when in place is retained by the bushing 58. When the parts are assembled, the pivot member 64 engaging the semicylindrical seats of the pivot members 55 and 56 maintains 50 the spacing between the ears, and the axis thereof is located midway thereof and extends in the direction of the vertical axis of the elevator when the sections are closed about a pipe.

The sections therefore toggle upon the pivot member 64 as an axis while they rock on the cross bars of the bails to bring the upper ends into gripping contact with the drill pipe and so that the seating faces of the ribs 15 and 16 engage the end of the coupling immediately adjacent the pipe as shown in Fig. 8. When the sections are open the ear 41 swivels upon the pivot member 55 and the pivot members 55 and 56 maintain their same relative relation with the ear of the other section due to the keying 60 pin 79 and the engagement of the pivot member 64 in the transverse recesses 62 and 63 of the pivot members 55 and 56. Attention is directed to the fact that the pin 70 serves merely to retain assembly of the sections and is not relied 65 upon to carry directly any of the thrusts imparted on the elevator under load of the drill pipe.

70 Formed on the side edges of the respective sections, opposite the universal hinge connection 75

39 just described, are lugs 83 and 84 arranged so that one lug is positioned above the other when the sections are closed. The lugs 83 and 84 project from the side faces 7 and 8 and are received in recesses 85 and 86 so that the sections may close without interference. The lugs are also spaced apart as indicated at 87 and the adjacent faces thereof are rounded as shown at 88 and 89 in Fig. 7 to accommodate rocking movement of the sections. Extending from the outer face of the elevator section 4 at one side of the lugs 83 and 84 are ears 90 and 91 mounting a pintle 92 on which a latch or link member 93 is pivotally mounted. The pintle 92 has a head 94 on the lower end and is retained from displacement by a cotter pin 95 extending through the upper end thereof and engaging the upper ear 90. The latch member 93 has a gate portion provided with an opening 96 having arcuate sides 97 and 98 corresponding to the side faces of the lugs so that the gate portion of the latch member is adapted to pass over the lugs and retain the sections in engagement about a pipe. The upper and lower faces of the opening 96 are spaced from the corresponding faces of the lugs as shown in Fig. 7 to accommodate shifting movement of the latch in respect to the lugs when the sections hinge to and from each other. Extending from the gate portion of the latch member are ears 99 and 100 mounted on the pintle 92 and respectively engaging the upper side of the ear 90 and the lower side of the ear 91 to maintain registering alignment of the opening 96 with the lugs 83 and 84. To limit opening movement of the latch, the ear 91 is provided with an outwardly and upwardly extending projection 101 to engage the outer side of the lower ear 100 when the gate portion of the latch has amply cleared the lugs. The latch is normally retained in latching engagement with the lugs by means of a coil spring 102 that is sleeved over the pintle 92 and has one end terminating in a laterally extending arm 103 which pressingly engages in a grooved seat 104 formed on the outer face of the latch as shown in Figs. 4 and 7. The opposite end of the spring terminates in a depending arm 105 that engages a side of the ear 91 as best shown in Fig. 1.

To facilitate release of the latch and opening of the elevator sections, each section is equipped with a handle or operating lever designated 106 for the section 3 and 107 for the section 4. The levers 106 and 107 are of similar construction and include heads 108 and 109 that are fixed to the upper ends of vertical shafts 110 and 111. The shaft 111 is relatively short and is rotatably mounted in an ear 112 projecting from the section 4 and in an extension 113 of the ear 90 as shown in Fig. 7, the ear 112 being spaced above the extension 113 to accommodate a hub 114 of a latch engaging arm 115, the hub of the arm being keyed to the shaft so that it is movable therewith upon swinging of the handle member. The free end of the arm terminates in a depending finger 116 that engages against an upwardly extending wing 117 on the gate portion of the latch member as shown in Figs. 4 and 7. It is thus obvious that when the handle 107 is swung to the right, Fig. 7, the finger 116 on the arm 115 pushes against the wing 117 on the gate portion of the latch member to swing it outwardly from engagement with the lugs 83 and 84 so that the sections may be opened upon applying spreading pressure to the handles 106 and 107.

The other shaft 110 is of longer length and is mounted in ears 118 and 119 projecting from the section 3 adjacent the upper and lower ends thereof. Fixed on the shaft at a point just over the upper lug 83 is an arm 120 that is normally seated in a recess 121 of the section 3 and which has an end 122 engaging the inner side of the gate portion of the latch member so that when the lever 106 is swung away from the lever 107 the shaft 110 is rotated to cause the cam-like head on the arm 120 to cooperate with the arm 115 in moving the latch member from engagement with the lug. The shaft 110 is normally retained in position so that the arm thereon is engaged in its recess by means of a coil spring 123 that is sleeved over the shaft and has one end engaging in a groove 124 of the shaft and its opposite end 125 engaging against the body of the section 3, as shown in Fig. 7. The shaft 111 is retained from longitudinal movement by the head of the lever 115 engaging one side of the ear 112 and the shaft 110 is retained by the head of a screw 126 that projects from the shaft and engages the lower side of the ear 118.

To prevent accidental release of the latch and provide a safety feature, each actuating lever 106 and 107 has a draw-bolt 127 slidable in a bore 128 extending longitudinally of the respective arms and engageable in sockets 129 formed in the sides of the respective sections as shown in dotted lines 30 in Fig. 3, the sockets 129 being located so that they register with the draw-bolts when the handles are in their normal position as shown in Fig. 2. Connected with the opposite ends of the draw-bolts are rods 130 extending through reduced continuations 131 of the bores 128 to intersect recesses 132 that are formed in the facing sides of the respective handles. Mounted in the recesses 132 is a tongue 133 of a release 134 having a substantially knob-like head 135 projecting from the recess so that it is adapted to be engaged by the thumb when the hands of the operator are placed on the respective levers, the tongues 133 being pivoted on pins 136 as shown in Fig. 2. The tongues have slots 137 through which the heads of the rods project and are pivotally secured therein by pins 138.

Sleeved on the rods are coil springs 139 having one of their ends engaging against the draw-bolts and their opposite ends against a shoulder 140 formed at the ends of the bores 128. It is thus obvious that the springs normally move the bolts to locking position but upon engagement of the knobs at the projecting ends of the levers the bolts are retracted against action of the springs to effect release of the handles. The heads of the handles or operating levers are partly positioned in recesses 141 and 142 of their respective sections and have laterally projecting lugs 143 and 144 adapted to engage the faces of the sections at the sides of the recesses 141 and 142 to limit outward movement of the handles with respect to the hinge sections of the elevator so that the latch release arms connected therewith are kept in position to engage the gate portion of the latch member when the sections are moved to and from closed position and to provide abutance whereby the opening force applied to the handles is transmitted to the sections so that they are caused to swing on their hinge connection.

Movement of the handle member 106 is limited in the opposite direction through engagement of the latch engaging arm 120 with the bottom of its recess 121 but due to the projection of the latch engaging arm of the other handle member, it is

necessary to provide the head of the handle member 107 with a lug 145 on the side opposite the lug 144 previously mentioned to engage the elevator section 4 at the side opposite the recess 142 as shown in Fig. 2.

The outer ends of the handles are provided with ball-like heads 146 to prevent slipping of the hands of the operator therefrom, and the inner ends of the handles are provided with transverse 10 ribs 147 to prevent slipping of the hands in the opposite direction where they might be injured by the actuating parts of the handles on swinging together of the elevator sections. It is obvious that with the handle structure just described, the 15 elevator latch may be operated by either one or both of the handles upon releasing the locking bolt for one or the other handle, or both.

The modified form of elevator illustrated in Figs. 12 to 17 inclusive operates on the same 20 principle as that of the preferred form and includes a collar or ring-like body 148 consisting of sections 149 and 150 corresponding to the sections 3 and 4 of the preferred form. In the modified form the universal hinge connection 25 consists of a ball and socket joint comprising hemispherical lugs 151 and 152 arranged reversely to each other and having flat faces 153 and 154 extending in spaced parallel horizontal planes to accommodate rocking movement of the sections. 30 The spherical portion 155 of the lug on one section engages within a spherical socket 156 of the other section when the sections are connected in hinged relation by means of a ball 159 that is seated in substantially hemispherical sockets 160 and 161 provided in the faces 153 and 154 35 of the respective lugs, the center of the sockets being common to the center of the spherical portions of the lugs.

In order to facilitate assembly, that portion of 40 the section 149 below the lug 151 is cut away and the cut away portion is applied as an insert 162 as clearly shown in Figs. 14 and 16. The sections may then be readily connected in hinged relation by inserting the ball 159 in the socket 160 and 45 moving the lug 151 into the spherical socket 156 of the section 150 until the ball 159 seats in the socket 161. The insert 162 is then applied which, when welded into position as indicated at 163, forms a key to retain the sections in hinged 50 relation. When thus connected the sections are free to hinge relatively to each other on an axis parallel to the axis of the pipe engaged thereby, as well as to rock toward each other on an axis parallel to the axes of the connecting portions 55 164 of the bails 165. The latch for securing the sections about a drill pipe is also of slightly different form. The sections are provided on opposite side edges thereof with lugs 166 and 167 having flat inner faces 168 forming continuations 60 of the adjacent edge faces 169 of the respective sections and having their opposite outer faces slightly rounded as at 170 to permit relative rocking movement of the sections when they are engaged by a coupling latch or link 171. The link 65 171 includes a substantially flat plate having a rectangular opening 172 therein to engage over the lugs 166 and 167 and which is provided with ears 173 and 174 that are hinged on a pin 175 carried by ears 176 and 177 projecting from the 70 outer side of the section 150. Sleeved over the pin 175 is a coil spring 178 having the ends 179 and 180 thereof engaging over the ears 173 and 174 of the coupling link or gate, the spring being so wound that the spring is normally retained in 75 yielding engagement with the ears.

To facilitate swinging movement of the link away from the lugs in opposition to action of the spring, the outer end thereof is provided with a U-shaped handle 181 (Figs. 12, 16 and 17). In this form of the invention the elevator section 150 is provided with a fixed handle 182 extending radially therefrom and terminating in a ball end 183. The handle 182 cooperates with a movable handle 184 pivotally supported on the other section and which has a similar ball end 185. The handle 10 184 is fixed to the squared end of a shaft 186 rotatably mounted in spaced ears 187 and 188. The shaft 186 has a laterally extending finger 189 that is normally engaged in a recess 190 in the section 149 and in position to engage against the 15 inner face of the coupling link 171 (Fig. 17), so that when the lever 184 is gripped to swing the sections apart the shaft 186 will be rotated, causing the finger 189 to move the link from latched engagement with the lugs 166 and 167. It is 20 therefore not necessary for the operator to grip the handle 181 to draw the coupling link from latched engagement with the lugs on the respective sections. To facilitate mounting of the shaft 186 in the ears 187 and 188 it is formed in two 25 sections 191 and 192, one of the sections having a dowel 193 engaged in a socket 194 in the abutting end of the other section. The sections when assembled are then secured by inserting a pin 195 through the upper section and through the 30 lower section as shown in Fig. 16.

In using the first form of elevator, for example, in pulling a string of drill pipe, the elevator is lowered into position for engaging under the coupling 20 of the pipe section projecting 35 from the rotary table (not shown). With the sections 3 and 4 in open position, as shown in Fig. 3, the operator will draw the elevator over the pipe, after which the handles are moved together until the gate portion of the latch member 93 swings 40 over the lugs 83 and 84. The gate, upon striking the lug 83, moves outwardly and slides over the end thereof until the lug is in registry with the opening 96, whereupon the stored up tension in the spring 102 will snap the latch member over 45 the lugs as shown in Fig. 1. Attention is directed to the fact that in this movement the gate merely moves over the lug 84 which is a part of the section on which the gate is pivotally supported. 50

When the elevator is raised the sections rock toward the pipe, toggling upon the pivot member 64, to engage under the coupling. The pipe is then raised in the derrick and while the pipe is supported by suitable slips on the turntable, the 55 upper pipe section is disconnected and swung by the elevator over toward the side of the derrick, whereupon the elevator is released by gripping the handles 106 and 107 and drawing them outwardly with respect to each other, at the same 60 time engaging the knob-like ends 135 of the release levers 134 to retract the bolts 127 from engagement with the sockets 129, thereby releasing the levers for rocking movement of the shafts 110 and 111 so that the gate contacting arms 65 thereon swing the gate to open position against action of the spring 102. Further movement of the handles causes the lugs 143 and 144 thereon to move in stopped engagement with the sections to swing the sections apart as shown in Fig. 3. 70 The elevator is then swung away from the pipe and lowered into engagement with the coupling on the next lower section to be removed from the well. The elevator is closed about the succeeding section in the manner above described. Atten- 75

tion is directed to the fact that when lifting force is applied to the elevator the inward pivoting movement of the elevator sections in effect causes contraction of the space between the upper ends 5 thereof to bring the edges of the seats 17 and 18 into engagement with the end of the coupling directly adjacent the periphery of the pipe so that even should the outer peripheral edge of the coupling be worn, the elevator grasps the unworn 10 portion to provide adequate support and prevent outward radial thrusts as above referred to.

The modified form of elevator operates in the same manner as the preferred form, the differences being merely in the construction of the 15 universal hinge connection and in the detail features of the machine.

From the foregoing it is obvious that I have provided an elevator construction particularly designed for safe manipulation of the drill pipe 20 when it is being drawn from or run into a well incidental to drilling operations and that the elevator is especially adapted for safe use in connection with drill pipe having worn collars.

What I claim and desire to secure by Letters 25 Patent is:

1. An elevator including a pair of sections having shape to encircle a pipe, bails having pivotal connection with the respective sections on substantially horizontal axes offset laterally on the 30 opposite sides of the encircled pipe whereon the sections are adapted to rock so that the upper portions thereof move into contact with the pipe, hinging means connecting adjacent sides of the respective sections, said hinging means having interacting axes respectively extending substantially parallel to the axis of the pipe encircled by the sections and to said horizontal axes of the bails whereon said sections are adapted to respectively close on the pipe and to pivot incidental 40 to rocking movement on the bail connections, and a latch releasably connecting the opposite sides of said sections and arranged to compensate for pivotal movement of the sections.

2. An elevator including sections having a 45 shape to encircle a pipe, supporting means having pivotal connection with the respective sections on substantially horizontal axes offset laterally on opposite sides of the axis of an encircled pipe whereon said sections are adapted to rock so that the upper portions thereof move into contact with the pipe, hinging means connecting adjoining ends of the sections and having a hinging axis extending parallel with said pipe axis and a hinging axis transversely intersecting the first hinging axis whereon said sections are adapted 55 respectively to swing open and close on the pipe and toggle incidental to said rocking movement of the sections, and means releasably connecting opposite ends of the sections to lock said sections together when encircling said pipe, said means being arranged to compensate for rocking movement of the sections.

3. An elevator including a pair of sections having a shape to encircle a pipe, supporting members having pivotal connection with the respective sections on substantially horizontal axes offset laterally on opposite sides of the axis of the encircled pipe whereon said sections are adapted to rock so that the upper portions thereof move into contact with the pipe, hinging means connecting the sections and having intersecting hinging axes, one of which extends substantially parallel with the axes of the supporting member connections and the other parallel with the axis of the encircled 70 pipe whereon said sections are respectively 75

adapted to swing open and close on the pipe to pivotally compensate for said rocking movement of the sections, and means releasably connecting the sections to lock the sections together when encircling said pipe, said means being arranged to compensate for rocking movement of the sections. 5

4. An elevator including a pair of sections adapted to encircle a pipe, universal hinging means connecting the sections at one side of the encircled pipe whereon said sections are adapted to swing to and from encircling relation with the pipe and whereon the sections are adapted to rock toward and away from each other, latch means connecting the sections at the opposite 15 side of the encircled pipe including lugs on the sections, a gate pivotally connected with one of the sections and movable over said lugs to rockingly retain said sections, operating levers pivotally mounted on the sections, and gate engaging 20 means having fixed connection with said operating levers to move said gate from engagement with said lugs when the operating levers are moved apart incidental to opening and closing the sections on a pipe, said gate and lug being 25 shaped to compensate for said rocking movement.

5. An elevator of the character described including mated sections, bails connected with said sections, a universal hinge connecting the sections together whereby the sections hinge relatively to each other for encircling a pipe and pivot toward each other on said bails to engage under a collar on said pipe, a lug on one of the sections, a link pivotally connected with the other section for engaging over the lug to retain the sections in encircling relation with the pipe, said lug and link having interengaging portions shaped to compensate for said pivoting movement of the sections, and means normally retaining the link in engagement with the lug. 30 35 40

6. An elevator of the character described including mated sections, bails connected with said sections, a universal hinge connecting the sections together whereby the sections hinge relatively to each other for encircling a pipe and pivot toward each other on said bails to engage under a collar on said pipe, a lug on one of the sections, a link pivotally connected with the other section for engaging over the lug to retain the sections in encircling relation with the pipe, said lug and link having interengaging surfaces shaped to compensate for said pivoting movement of the sections, a spring normally retaining the link in engagement with the lug, and means on one of the sections having contact with the link 50 55 for releasing the link from engagement with the lug incidental to hinging of the sections away from said pipe.

7. An elevator of the character described including mated sections, bails connected with said sections, a universal hinge connecting the sections together whereby the sections hinge relatively to each other for encircling a pipe and pivot toward each other on said bails to engage under a collar on said pipe, mating lugs on the sections, a link pivotally connected with one of the sections for engaging over the lugs to retain the sections in encircling relation with the pipe, said lugs and link having interengaging surfaces shaped to compensate for said pivoting movement of the sections, and a spring normally retaining the link in engagement with the lugs. 60 65 70

8. An elevator of the character described including a pair of mated members, bails connected with said members, a universal hinge directly 75

connecting the members together whereby the members hinge relatively to each other for encircling a pipe and pivot toward each other on said balls to engage under a collar on said pipe, 5 lugs on the members, a link pivotally connected with one of the members for engaging over the lugs to retain the members in encircling relation with the pipe, said lugs and link being arranged to compensate for said pivoting movement of the members, a spring normally retaining the link in engagement with the lugs, and means on one of the members having contact with the link for releasing the link from engagement with the lugs incidental to hinging of the members away from 10 said pipe.

9. An elevator including a pair of sections having shape to encircle a pipe, balls having pivotal connection with the respective sections on substantially horizontal axes offset laterally on the opposite sides of the encircled pipe whereon the sections are adapted to rock so that the upper portions thereof move into contact with the pipe when lifted by said balls, a hinging ear on one section and having a bore extending substantially 20 parallel with the axis of the encircled pipe, a pivot member in said bore having a bearing seat arranged with an axis extending transversely with respect to said bore, a transverse pivot member in said seat, means on the other section supporting said transverse pivot member whereby said sections are adapted to pivot relatively to said transverse axis incidental to rocking movement thereof on the ball connections, and cooperating latch members connecting the sections 30 and arranged to compensate for pivotal movement of the sections on said transverse axis.

10. An elevator of the character described including a pair of members, a ball connected with each of the respective members, means universally hinging the members together for pivotal movement on a point offset but in a plane passing through the axis of a pipe to be engaged by said members and whereon the members hinge relatively to each other and pivot toward each other 40 to engage under a collar on the pipe, and a latch on one of said members and engageable with the other member to retain the members in encircling relation with the pipe, said latch being formed to compensate for pivotal movement of the members toward each other.

11. An elevator including a pair of sections having shape to encircle a pipe, balls having pivotal connection with the respective sections on substantially horizontal axes offset laterally on the opposite sides of the encircled pipe whereon the sections are adapted to rock so that the upper ends move into contact with the pipe when lifted by said balls, hinging ears on the respective sections and having registering bores extending 50 parallel with the axis of the encircled pipe, pivot members in said bores having semi-circular bearing seats arranged with a common axis extending parallel with the axes of the ball connections, a cylindrical pivot member received in said seats and on which said sections are adapted to pivot incidental to rocking movement thereof on the ball connections, means connecting said ears to retain the pivot members, a latch releasably connecting the opposite side of said sections and arranged to compensate for pivotal movement of the sections on said pivot members, and means 60 anchoring one of said first named pivot members in its bore to maintain fixed axial relationship of said cylindrical pivot member with one of the sections.

12. An elevator including a pair of sections having shape to encircle a pipe, balls having pivotal connection with the respective sections on substantially horizontal axes offset laterally on the opposite sides of the encircled pipe whereon the sections are adapted to rock so that the upper portions thereof move into contact with the pipe when lifted by said balls, hinging ears extending from adjacent sides of the respective sections and having registering bores extending parallel 10 with the axis of the encircled pipe, pivot members in said bores having bearing seats arranged with a common axis extending parallel with the axes of the ball connections, a pivot member in said seats and on which said sections are free to 15 pivot incidental to rocking movement thereof on the ball connections, means connecting said ears to retain the pivot members, and a latch releasably connecting the opposite sides of said sections and arranged to compensate for pivotal movement of the sections on said pivot members.

13. An elevator of the character described including mated sections, balls connected with said sections, means hinging the sections together whereby the sections hinge relatively to each other to encircle a pipe and pivot toward each other on said balls to engage under a collar on said pipe, a latch on one of said sections and engageable with the other section to retain the sections in encircling relation with the pipe, fixed 30 and movable levers on the sections, and means connected with the movable lever for releasing the latch.

14. In a device of the character described, a pair of sections adapted to encircle a pipe, a ball 35 and socket hinge connecting the sections, and a latch cooperating with said ball and socket connection to retain the sections in encircling relation with the pipe.

15. An elevator of the character described including mated sections, balls connected with said sections, a ball and socket hinge connecting said sections, and a latch cooperating with said ball and socket connection to retain the sections in encircling relation with a pipe.

16. In a pipe supporting mechanism, a pair of sections having shape to encircle a pipe, means hingedly connecting the sections including a single rigid projection on adjacent sides of each section, a pivot member interposed between said 40 projections and having intersecting horizontal and vertical axes and opposed arcuate faces centered with the respective axes, said projections being provided with corresponding arcuate bearing surfaces to engage said arcuate faces, and means for retaining said pivot member between said projections whereby said sections are adapted to move relatively to each other on said 50 arcuate faces.

17. An elevator of the character described including mated sections, balls connected with the sections, complementary hemispherical shaped lugs on each of the respective sections and engaged in a spherical recess of the other section, said lugs having registering ball sockets, a ball 60 mounted in said sockets for hingedly retaining the sections, and a latch for retaining the sections in encircling relation with a pipe to be moved by the elevator.

18. An elevator of the character described including mated sections having spherical recesses in adjacent sides thereof, complementary hemispherical shaped lugs on the respective sections and engaging in the spherical recesses and provided with registering spherical sockets, a ball 70 75

mounted in said sockets for retaining the sections in universal hinged relation, bails connected with the respective sections, and a latch connecting the opposite sides of said sections to retain the 5 sections in encircling relation with a pipe.

19. An elevator of the character described including mated sections having spherical recesses in one of their adjacent sides to form a hinge socket, hemispherical shaped lugs on the sections 10 and engaging in said hinge socket, said lugs having flat faces and aligning ball sockets, a ball in said sockets and retaining said faces in spaced parallel planes to effect universal movement of 15 said sections relatively to the axis of a pipe engaged by said sections, and latch means connecting the opposite side of the sections to retain the sections in encircling relation with the pipe.

20. An elevator of the character described including two mated sections, a ball and socket 20 joint connecting the sections for effecting movement of the sections with respect to vertical and horizontal planes through the vertical axis of the elevator, and locking means connecting the sections in encircling engagement with an object 25 carried by the elevator.

21. In an elevator of the character described, a pair of sections having shape to encircle a pipe, a hinge forming member on each section, and universal means interposed between said members 30 whereby the sections are adapted to swing to and from encircling relation with an encircled pipe and to rock to and from engagement with said pipe.

22. In a pipe supporting mechanism, a pair of sections having shape to encircle a pipe and means hingedly connecting the sections including a single rigid projection on adjacent sides of each section, and a hinge mechanism connecting said 5 projections and having horizontal and vertical hinging axes.

23. In a pipe supporting mechanism, a pair of sections having shape to encircle a pipe, means hingedly connecting the sections including a rigid 10 projection on adjacent sides of each section and having registering bores, cylindrical pivot members mounted in the bores and having cylindrical recesses extending transversely of the bores, a pivot member in said recesses, and a retaining pin 15 extending through said projections and said pivot members axially of said bores whereby said sections are adapted to hinge on the first named pivot members and to pivot to and from each other on the last named pivot member. 20

24. An elevator including pivotally connected sections having shape to encircle a pipe, a latch mechanism connecting the sections for holding the sections in encircling relation with the pipe, a latch operating lever pivotally mounted on the 25 upper portion of one of the sections and projecting radially therefrom to form a handle, and means connecting said lever with the latch mechanism.

GEORGE KRELL. 30
